B.F. Joslyn,
Pump Lift,
No 12,631, Patented Apr. 3, 1855.

UNITED STATES PATENT OFFICE.

BENJAMIN F. JOSLYN, OF WORCESTER, MASSACHUSETTS.

DOUBLE-ACTING PUMP.

Specification of Letters Patent No. 12,681, dated April 3, 1855.

To all whom it may concern:

Be it known that I, BENJAMIN F. JOSLYN, of the city and county of Worcester and State of Massachusetts, have invented a new 5 and useful Improvement in Pumps; and I do hereby declare that the following is a full, clear, and exact description of the construction and operation of the same, reference being had to the drawings herewith 10 presented making a part of this specification.

My improvement consists in making a passage or waterway through the piston and the end of the cylinder by attaching a tube, 15 A, (see drawing) to the piston L, extending through a stuffing box in the end of the cylinder and allowing it to play with the piston, the tube being provided with a valve H on the piston to prevent the return of 20 the water; the other parts may be of any of the usual forms of double acting pumps in common use.

The operation of my pump is on moving the piston toward D the part C will be filled 25 through a valve in the end of the cylinder as F in the usual way (water being supplied at B,) and when the piston is moved toward C the part D will be filled by the water passing through the tube A and valve H as indicated by the arrows while the water in 30 part C is discharged through valve E to the air chamber M and on the return stroke the water in D is similarly discharged through G.

I do not claim placing cylinders in any 35 particular position in regard to the air chamber or other parts nor the exact form or proportions of any of the valves tubes or other parts. But

What I do claim as new and desire to secure by Letters Patent is—

I claim forming a direct passage to admit fluids to one part of the cylinder by means of a tube attached to and working with the piston and passing through the other part 45 and end, when applied to double acting pumps as above described, or any other substantially the same.

BENJ. F. JOSLYN.
